United States Patent Office.

CHARLES B. STEPHENS, OF RIVERTON, CONNECTICUT.

Letters Patent No. 96,845, dated November 16, 1869.

IMPROVEMENT IN ENVELOPE-OPENERS.

The Schedule referred to in these Letters Patent and making part of the same

To all whom it may concern:

Be it known that I, CHARLES B. STEPHENS, of Riverton, in the county of Litchfield, and State of Connecticut, have invented a new and useful Improvement in Combination Envelope-Opener; and I do hereby declare that the following is a full, clear, and exact description thereof, which will enable others skilled in the art to make and use the same, reference being had to the accompanying drawings, forming part of this specification.

This invention relates to a new and useful improvement in an instrument for opening envelopes of letters, public documents, &c.; and consists in a peculiarly-formed cutting-blade and handle, and also in combining therewith an ink and a lead-eraser, as herein-after more fully described.

In the accompanying drawings—

Figure 1 represents a side view, and

Figure 2, an edge view of the instrument.

Similar letters of reference indicate corresponding parts.

A represents the blade, which is formed (in the outline) something like the ordinary eraser-blade, at and near its point, but it has either one or two cutting-points B, in the form of barbs, as seen in fig. 1.

C is the handle, which is of metal or other suitable material. Its edges are grooved, as indicated by the dotted lines in fig. 1.

The handle extends forward in a spear-shape, and is bisected so that the blade A is fastened by screws between the parts, as seen in fig. 2.

By fastening the blade with screws, it can be readily removed for sharpening the points B.

The position of these points corresponds with the centre of the grooves d of the handle, but they are slightly raised from the bottom of the groove, so that when the instrument is drawn in contact with the edge of an envelope, the point will enter just inside the fold, and cut the paper at the fold, while the groove d acts as a guide for keeping the edge of the envelope in the proper position while being cut.

F represents an India-rubber eraser, which is fastened to the back end of the handle by rivets or screws, or in any other suitable manner.

It will thus be seen that three useful articles are combined in this instrument, each durable, as regards its construction, and perfect in its operation.

Having thus described my invention,

I claim as new, and desire to secure by Letters Patent—

1. The eraser-blade A, (with one or more points B,) in combination with a grooved handle, and operating substantially as described, for the purposes set forth.

2. In combination with the blade A and handle C, the lead-pencil eraser F, substantially as described.

3. The combination of an ink and lead-eraser with an envelope-opener, substantially as described.

CHARLES B. STEPHENS.
